United States Patent Office

Des. 181,932
Patented Jan. 21, 1958

181,932

SOFA

John J. Lubberts and Lambert J. Mulder, Grand Rapids, Mich., assignors to Tomlinson of High Point, High Point, N. C., a corporation of North Carolina

Application April 12, 1957, Serial No. 45,710

Term of patent 14 years

(Cl. D15—11)

Fig. 1.

Fig. 2.

Fig. 3.

Fig. 4.

We claim:

The ornamental design for a sofa, substantially as shown.
